UNITED STATES PATENT OFFICE.

JAMES H. SMITH, OF CHICAGO, ILLINOIS.

VIGNETTER.

SPECIFICATION forming part of Letters Patent No. 774,457, dated November 8, 1904.

Application filed February 17, 1904. Serial No. 194,048. (No model.)

To all whom it may concern:

Be it known that I, JAMES H. SMITH, a citizen of the United States, residing at Chicago, in the county of Cook and State of Illinois, 5 have invented new and useful Improvements in Vignettters, of which the following is a specification.

My invention relates to devices for vignetting photographic negatives while they are 10 exposed in the camera. It produces all the effects characteristic of these machines and in a more nearly perfect degree, while it is very simple and durable in construction, is very easily manipulated, and is of moderate 15 cost.

The accompanying drawings illustrate the invention, in which—

Figure 1 is a side elevation of the device attached to the top of a camera-stand and 20 with the blender in a vertical position. Fig. 2 is a plan view with the blender inclined backward. Fig. 3 is an enlarged plan of a modification of the end of the adjusting-rod. Fig. 4 is an enlarged rear elevation of the 25 supporting mechanism, partly in section, on line $\alpha\alpha$ of Fig. 2. Fig. 5 is an enlarged rear elevation of the blender, and Fig. 6 is an enlarged side view of the blender-frame clamp.

Letters of reference indicate the various 30 features of the invention, similar letters denoting corresponding parts in the several views.

The letter A indicates the top of a camera-stand, to which the vignetter is attached.

35 B is the vignetter-holder, having jaws b b' and a thumb-screw b' , by which the holder is secured to the stand.

C is a vertical post fixed on the holder B.

40 D is a vertically-bisected preferably spherical and hollow clamp and having recesses d d' in one of its members to receive the post C and being rotatable and vertically adjustable on said post.

E is a pipe which rests in recesses d d' in 45 the other member of said clamp. The recesses d and d' are located at the inner opposite edges of the clamp D and are only deep enough to receive a part of the thickness of said post and pipe, the projecting parts of 50 said post and pipe being forced against each

other or against the opposite side of the clamp by the pressure of the hand-nut F as it is screwed upon the threaded bolt f , which extends centrally and horizontally through the clamp D. 55

The pipe E is rotatable, tiltable, and longitudinally movable in the clamp D and may be held rigidly in any desired position by the said nut and screw or when held with only a moderate grip may be rotated, tilted, or swung 60 right and left without changing the pressure of the nut F.

A hand-wheel e is provided on the rear or operator's end of the pipe E, by which it is moved, and an arm e' , having a clamping-jaw 65 e'' , is provided at its front end.

A rod G, having a hand-ball g , extends through pipe E, its front end having a plate g' with a vertical slot g'' therein. This end of the rod G may itself be bent into the form 70 shown in Fig. 3, in which the loop g'' will serve the same purpose as the slot g'' in the plate g' .

H is the blender-frame, preferably made of heavy wire bent to form the two ends and a 75 side of a rectangle and having flanges h h' to hold the blender-card I. A shaft h' , with an oscillating arm h'' at a right angle thereto, extends from the frame H and is movably clamped by the jaws e'' above mentioned, said 80 arm h'' passing loosely through the slot g'' in the plate g' .

By pushing forward or drawing back the rod G the blender is caused to incline as desired, its axial line at the deepest part of the 85 notched curve i remaining substantially in the same position with reference to the focal point of the camera.

It is evident that with this construction the blender may readily be moved nearer to or 90 farther from the camera, that it may be inclined forward or backward, or be swung upward or downward and right or left, as desired, by manipulating the wheel e or ball g , which are placed conveniently for the operator. 95

What I claim, and desire to secure, is—

1. In a vignetter attachable to a camera-stand, a holder having jaws to engage said stand, a set-screw to bind said jaws thereon a 100

vertical post on said holder and a vertically-bisected clamp on said post, for the purpose stated.

2. In a vignetter, a holder having a fixed vertical post, a vertically-bisected clamp, one of whose members has recesses to engage said post, the other of said members having recesses to engage a pipe, and means to adjustably bind said post and said pipe in said clamp for the purpose specified.

3. In a vignetter having a holder with a vertical post, a bisected clamp on said post, a screw and nut to hold the members of said clamp together, recesses d in the edge of one of said members to engage said post, recesses d' in the edge of said other member, a pipe in said recesses d' , said post and said pipe contacting under pressure of said screw and nut as described.

4. In a vignetter-holder having a fixed ver-

tical base, means for detachably fastening the said base to the camera-stand, a bisected clamp one of whose members has recesses to engage said base, the other of whose members has recesses to engage a pipe and means for adjustably binding said base and said pipe in said clamp, for the purpose specified.

5. In a vignetter having an adjusting-pipe, an arm thereon, a clamp on said arm, a shaft connected with the blender-frame, an arm on said shaft and a rod extending through said pipe having a terminal slot adapted to engage said arm on said shaft.

In testimony whereof I have signed my name to this specification in the presence of two sub- 35 scribing witnesses.

JAMES H. SMITH.
